UNITED STATES PATENT OFFICE.

REGINALD A. FESSENDEN, OF BROOKLINE, MASSACHUSETTS, ASSIGNEE TO SUBMARINE SIGNAL COMPANY, OF PORTLAND, MAINE, A CORPORATION OF MAINE.

DYNAMO-ELECTRIC MACHINERY.

1,213,611.

Specification of Letters Patent. Patented Jan. 23, 1917.

Original applications filed January 29, 1913, Serial No. 744,793, and May 31, 1913, Serial No. 770,657. Divided and this application filed October 4, 1915. Serial No. 53,895.

To all whom it may concern:

Be it known that I, REGINALD A. FESSENDEN, of Brookline, in the county of Norfolk and State of Massachusetts, a citizen of the United States, have invented certain new and useful improvements in Dynamo-Electric Machinery, of which the following is a specification.

The invention herein described relates to electro dynamic apparatus and methods and to the generation, the utilization, the transmission and the receipt of electric energy and more particularly to the production and detection of compressional waves, and still more particularly to submarine signaling.

It has for its object increased efficiency in these lines.

This application is a division of the application filed by me which matured into Letters Patent No. 1,167,366, issued January 4, 1916, which was a division of my application Serial No. 744,793, filed January 29, 1913.

The invention will be understood more particularly by reference to the drawings in which it is shown in its preferred embodiment.

In the drawings Figure 1 is a diagrammatic cross section of a reciprocating dynamo capable of being used in carrying out my invention. Fig. 2 illustrates the application of a gas engine to such dynamo.

A suitable form of apparatus for carrying out this invention is shown in Fig. 1. Here 40 is a copper tube say approximately eight inches in diameter and eight inches long (the length being preferably equal to or less than the diameter). 45-45 is the magnetizing coil of the magnetic circuit, 43-43 being the north pole and 44-44 being the south pole. The magnetic flux flows from 43-43 through the top air gap to the armature or core 41, thence through the bottom air gap 44-44 and back through the outside ring to 43-43. The tube 40 lies in the two air gaps and such part of it as is not over the windings 46, 47, is preferably slotted as at 66 or otherwise made of high resistance. The windings 46, 47 are preferably wound on the core 41 though they may be wound on the inside of the poles 43-43, 44-44. The core 41 and the poles are preferably slotted vertically and radially as

at 67 and 68, respectively. The core 41 is preferably made of iron and the poles are 55 preferably made of soft steel or wrought iron, tube 40 being attached in any suitable manner to the object to be set in motion or attached to the piston of an engine as shown in Fig. 3. As shown these two windings 46, 47 are two coils of a single winding though two windings may be used in which case there would be additional terminals.

My invention forms a very efficient generator of alternating currents. The tube 40 may be fixed directly to the piston rod of a gas engine as in Fig. 3 where 70 indicates the cylinders of the gas engines, the pistons 71 being set to operate in opposite 70 directions to each other. Where a number of such units are used they may be connected in parallel, and the synchronizing effect is so strong that no crank shafts or fly wheels are necessary and the governing 75 can be done by timing the ignition alone. This is of great importance with engines of the type invented by me where the power per cylinder is so great that the crank shaft if it transmitted the power would 80 have approximately the same diameter as the cylinder.

What I claim as my invention is:—

1. Apparatus for generating electrical power, comprising a plurality of reciprocating engines and a plurality of reciprocating dynamos operatively connected to said heat engines, said reciprocating dynamos being electrically connected with each other and having substantially no self induction, being thereby maintained in synchronism.

2. Apparatus for generating alternating electrical power comprising a plurality of reciprocating engines and a plurality of reciprocating dynamos operatively connected to said engines, said reciprocating dynamos being electrically connected with each other and having substantially no self induction, being thereby maintained in synchronism, and the frequency of the currents rendered independent of any natural period of the engine.

3. Apparatus for generating electrical power comprising a plurality of reciprocating engines and a plurality of reciprocating alternating dynamos operatively connected

to said engines, said reciprocating dynamos being electrically connected with each other, and having substantially no self-induction, being thereby maintained in synchronism, 5 and the frequency of the currents generated rendered independent of any natural period of the engines.

4. Apparatus for generating electrical power comprising a plurality of engines 10 and a plurality of reciprocating alternating dynamos operatively connected to said engines, said reciprocating dynamos being electrically connected with each other and having substantially no self-induction, be- 15 ing thereby maintained in synchronism.

5. Apparatus for generating alternating electrical power comprising a plurality of engines and a plurality of reciprocating dynamos operatively connected to said engines, 20 said reciprocating dynamos being electrically connected with each other and having substantially no self-induction, being thereby maintained in synchronism.

6. Apparatus for generating alternating electrical power comprising a plurality of 25 explosion engines and a plurality of recip-

rocating dynamos operatively connected to said engines, said reciprocating dynamos being electrically connected in parallel with each other and having substantially no self- 30 induction, being thereby maintained in synchronism.

7. Apparatus for generating electrical power comprising a plurality of explosion engines and a plurality of reciprocating alternating dynamos operatively connected to said engines, said reciprocating dynamos being electrically connected in parallel with each other and having substantially no self- 35 induction, being thereby maintained in syn- 40 chronism.

8. Apparatus for generating electrical power comprising a plurality of engines and a plurality of reciprocating dynamos operatively connected to said engines, said recip- 45 roating dynamos being electrically connected in parallel with each other and having substantially no self-induction, being thereby maintained in synchronism and adjustable in speed independently of the natural 50 frequencies of the engines.

REGINALD A. FESSENDEN.
